UNITED STATES PATENT OFFICE.

ANSON A. SCHRODER, OF VAN HORN, IOWA, ASSIGNOR OF ONE-HALF TO
A. H. SCHRODER, OF SAME PLACE.

TOBOGGAN.

SPECIFICATION forming part of Letters Patent No. 364,306, dated June 7, 1887.

Application filed February 17, 1887. Serial No. 227,892. (No model.)

To all whom it may concern:

Be it known that I, ANSON A. SCHRODER, a citizen of the United States, residing at Van Horn, in the county of Benton and State of Iowa, have invented certain new and useful Improvements in Toboggans or Coasters, of which the following is a specification.

The object of my invention is to produce a coaster which shall combine the flexibility and lightness of the common toboggan with the comfort, safety, and speed of the common sled.

The invention consists, essentially, in forming the toboggan of two thin runners suitably connected and stayed; in providing the same with an elevated seat-board; in so arranging and constructing the parts that they may move upon each other to admit of the requisite flexibility; in providing the runners with lateral guards to prevent contact of the hands or other parts of the body, or of the body of the toboggan with the side of the chute; in a novel arrangement of the side rail, and in the general construction and adaptation of the device to the ends intended, as will be hereinafter fully set forth and claimed.

In the accompanying drawings, forming a part of this specification, Figure 1 represents a side elevation of the invention; Fig. 2, a plan view of the same; Fig. 3, a front elevation of the same, and Fig. 4 a rear elevation of the section indicated by the line $y z$ of Fig. 2.

Similar letters of reference indicate corresponding parts.

The lightness, flexibility, and beauty of the common toboggan are offset by several undesirable qualities which it is the design of this invention to remove. Chief among these are the excessive friction opposed to the ice by the broad bottom, the uncomfortable position of the rider incident to its peculiar construction, and its common liability to injure the hands of the rider by contact with the side of the chute or slide. To improve the toboggan in these and other respects the following means are employed:

A. A are two thin broad runners, preferably, though not necessarily, plano-convex in cross-section, as shown, the object of this formation being, of course, to decrease the friction. In practice I make these runners about one-quar-

ter the entire width of the toboggan, though this is largely a matter of taste. They should, however, be made thin enough to admit of that flexibility which is a valuable feature of the toboggan. When designed for use in a chute, 55 they may be curved at each end, as shown in Fig. 1; but for ordinary coasting the rear end is preferably left straight, as in Fig. 2, so that the steersman may occupy that position. The runners are set some distance apart, say about twice their own width. In practice I draw the ends of the curves together, as shown, and fasten them in this position by a suitable stay, 60 b. The effect of this is to truss the parts in a measure, and thus materially strengthen the toboggan, as well as to impart a novel and pleasing appearance to the same. It is not, however, absolutely necessary that this should be done, since the curve may be brought back parallel with the runner and connected in that 65 position with a transverse stay or brace in substantially the same manner.

The runners are connected at proper intervals by knees D D' D', which may be of wood, in the nature of sled-knees, but are preferably 70 made of iron or steel, the latter being represented in the drawings. These are fastened to the runners by suitable rivets, bolts, or screws, as indicated in Fig. 4. It is desirable to make the middle knee, D, somewhat heavier and 75 stronger than the others, as it is designed to connect the seat-board B to this knee alone, allowing it to simply rest upon the others. The effect of this is to impart the desired flexibility to the toboggan, the seat-board being 80 free to slip endwise, according to the twist or curvature of the runners. As will be seen, the seat-board is considerably elevated above the runners and occupies a position about midway between them. The object of this is to 85 make the toboggan more comfortable to sit on than the common one, the rider in this case sitting astride the seat, or sidewise thereon, and resting the feet on the runners at the side.

A side rail, C, serves the double purpose of 90 a hand-rail for the steersman and a foot-rail for the others. For the same reason stated above, this rail should be fastened only to the middle bracket or knee, and be free to slip in its other bearings, as shown.

Instead of the cord or like device commonly used for holding the curved end of the toboggan in position, I connect the ends of the runners in this device with the seat-board by means 5 of light angle-irons *a a*. These may be separate irons, as shown, hooking under each side of the board, or a continuous strap, as indicated by the dotted line in Fig. 3. In the same manner the seat-board is loosely connected with 10 the terminal knees by longitudinal straps *c c*. The whole toboggan is thus bound securely, but flexibly, together.

Near the ends of each runner are attached lateral guards *E E*, which project beyond the 15 line of any other part of the toboggan and prevent the same from running foul of the side of the chute or other obstruction, thus preventing the injury to the toboggan or its occupant above referred to. The form of this, 20 as well as other parts, may be varied, of course, from that shown without departing from the spirit of the invention,

While I regard the device in the form shown as best adapted to the ends in view, I do not 25 regard each part as indispensable, nor the particular form or material as necessary to the operativeness of the invention. Thus, instead of the runners being separated, as shown, the elevated seat which I claim may be used in 30 connection with a solid bottom; so, also, the rail or the lateral guards might be dispensed with without affecting the other features of the invention.

Having thus described my invention, what I 35 claim as new, and desire to secure by Letters Patent, is—

1. In a toboggan or coaster, the combination of broad vertically-flexible runners or body, knees adapted to support an elevated 40 seat-board, and a seat-board having a fixed connection with but one of its supports, substantially as and for the purpose set forth.

2. In a toboggan or coaster, the combination of two broad vertically-flexible runners, separated, and having converging curved ends, 45 connecting knees adapted to support an elevated seat-board, and a seat-board mounted thereon with but one fixed longitudinal connection, substantially as described.

3. In a toboggan or coaster, the combination 50 of the flexible body, substantially as described, an elevated seat-board having but one longitudinal connection with the toboggan, knees adapted to support said seat-board and having outwardly-projecting arms relatively lower 55 than the seat-supporting portion, and a foot or hand rail fixed to but one of said arms, substantially as described.

4. In a toboggan or coaster, the combination 60 of two separate laterally-broad and vertically-thin runners, connecting knees or brackets, and an elevated seat mounted on said knees and having a free longitudinal movement on all but one of them, whereby the toboggan is made flexible, substantially as specified. 65

5. In a toboggan or coaster, the combination 70 of the runners *A A*, knees *D D' D'*, the seat-board *B*, fastened rigidly to the knee *D*, and loosely secured to the terminal knees by the strap *c*, substantially as and for the purpose set forth.

6. In a toboggan or coaster, the combination 75 of the seat-board *B*, permanently but loosely mounted on the knees *D D'*, the curved runners *A A*, and the keepers *a a*, substantially as and for the purpose specified.

7. In a toboggan or coaster, the combination 80 of the runners, substantially as specified, having inwardly-converging curved ends, a connecting-piece, *b*, having keepers *a a*, and a seat-board mounted substantially as described, and adapted to slip endwise in said keepers, substantially as set forth.

8. In a toboggan or coaster, the combination 85 of the vertically-flexible runners *A A*, the knees *D D' D'*, the elevated central seat-board, *B*, fastened rigidly to only one of said knees, and the rail or fender *C*, similarly secured, substantially as and for the purpose specified.

In testimony whereof I affix my signature in presence of two witnesses.

ANSON A. SCHRODER.
